CENTRIFUGAL PUMP

Kenneth R. Lung, Dayton, Ohio, assignor to The Tait
Manufacturing Company, a corporation of Ohio

Application June 6, 1955, Serial No. 36,384

Term of patent 14 years

(Cl. D65—1)

Fig. 1 is a perspective view of the centrifugal pump embodying my new design;

Fig. 2 is a side elevational view of the centrifugal pump of Fig. 1; and

Fig. 3 is an end elevational view looking from right to left in Fig. 2.

The other side of pump is substantially like the side shown in Figs. 1 and 2 except for the boss which appears at the upper right hand corner in Figs. 1 and 3.

The design is characterized by the features illustrated in full lines in the drawing.

I claim:

The ornamental design for a centrifugal pump, substantially as shown and described.
